DESIGN FOR A SHOE

Charles Morali, Forest Hills, N. Y., assignor to Delman, Inc., New York, N. Y.

Application September 25, 1934, Serial No. 53,392

Term of patent 3½ years

To all whom it may concern:

Be it known that I, Charles Morali, a citizen of the United States and resident of Forest Hills, in the county of Queens and State of New York, have invented a new, original, and ornamental Design for Shoes, of which the following is a specification, reference being had to the accompanying drawing, in which:

The dominant feature of my invention comprises the ornamental band A tapering upwardly from the sole over the vamp and extending to form a collar for the throat of the shoe, and a similar band B tapering upwardly from the shank portion over the counter and extending to form a collar for the inner quarter of the shoe.

I claim:

The ornamental design for a shoe as shown and described.

Dated, New York, September 19, 1934.

CHARLES MORALI.
